S. W. REYNOLDS.
REIN SPREADER AND GUIDE FOR HARNESS.
APPLICATION FILED JUNE 28, 1920.

1,406,415.

Patented Feb. 14, 1922.

UNITED STATES PATENT OFFICE.

SAMUEL W. REYNOLDS, OF SCRANTON, PENNSYLVANIA, ASSIGNOR TO REYNOLDS MANUFACTURING COMPANY, OF TOLEDO, OHIO, A CORPORATION OF OHIO.

REIN SPREADER AND GUIDE FOR HARNESS.

1,406,415.

Specification of Letters Patent. Patented Feb. 14, 1922.

Application filed June 28, 1920. Serial No. 392,209.

To all whom it may concern:

Be it known that I, SAMUEL W. REYNOLDS, of Scranton, in the county of Lackawanna, in the State of Pennsylvania, have invented 5 new and useful Improvements in Rein Spreaders and Guides for Harness, of which the following, taken in connection with the accompanying drawings, is a full, clear, and exact description.

10 This invention relates to a rein spreader and guide for harnesses of the class set forth in the patent to Mathias No. 700,795, May 27, 1902, in so far as it makes use of a pair of similar but reversely arranged roller supporting sections having portions thereof overlapping one upon the other and provided with loops for receiving a spreader strap, but differs therefrom in certain structural features, viz: first, in pivoting said members 15 within and coaxial with the roller so that they may be folded and unfolded upon and from each other about said axis; second, in providing the sections with interlocking members to hold them against relative lateral movement when folded one upon the other; third, in providing the roller with interior sheet metal linings or bearings for receiving the pintles of the folding sections, and fourth, in providing the sections with 20 means for holding the sheet metal linings or bearings against axial displacement from their respective pintles.

The main object is to increase the general working efficiency and durability of a device 25 of this character, and, at the same time, to facilitate and reduce the cost of assembling by permitting the pintles with the sheet metal bearings thereon to be easily and quickly assembled in the roller independently of each other with the assurance that the sheet metal bearings will be firmly held in the roller against rotation, and at the same time, to enable the roller with the sheet metal linings therein to rotate freely upon the 30 pintles without binding or liability of axial displacement.

Another object is to provide means for assisting the spreader strap in holding the sections against lateral displacement when 35 folded one upon the other.

Other objects and uses relating to specific parts of the device will be brought out in the following description.

In the drawings:

55 Figure 1 is a side elevation and Figure 2

a top plan of a rein spreader and guide embodying the various features of my invention, the spreader strap and rein being shown partly in section in Figure 2.

Figure 3 is a sectional view partly in plan of the same device with the sections unfolded.

Figure 4 is a longitudinal sectional view taken on line 4—4, Figure 2.

As illustrated, this device comprises a two-part metal frame composed of similar but reversely arranged U-shaped sections —1— and —2—, a roller —3— and sheet metal bushings or linings —4—, which are tightly fitted in the central lengthwise circular opening —5— in the roller —3—. One of the arms of each of the sections —1— and —2— constitutes a pivotal stud or pintle —6— of approximately one-half the length of the roller —3—, said pintles being inserted from 70 opposite ends of and into the central opening —5— in the roller and also within their respective sleeves or bushings —4—, so that their adjacent ends lie in close proximity substantially midway between the ends of 75 the roller.

The sleeves —4— are also of substantially one-half the length of the roller and are preferably split through one side and placed over and upon their respective pintles —6— 80 between inner and outer annular shoulders —7— and —8— prior to the insertion of said pintles and sleeves within the lengthwise opening —5— of said roller, said annular shoulders serving to hold the sleeves against 85 axial displacement upon their respective spindles when the parts are assembled for use, and also during the operation of forcing the pintles with the sleeves thereon into the roller through opposite ends of the opening 90 —5—.

The other arms, as —9— and —10— of the sections —1— and —2— are integrally united to the outer ends of their respective sections —1— and —2— by connecting bars 100 —11— which are of sufficient radial length to hold the arms —9— and —10— some distance from the periphery of the roller —3—.

These arms —9— and —10— are substantially flat and parallel with pintles —6— 105 and are located substantially the same distance from the axis of said pintles or roller —3— so as to lie flatwise one upon the other when folded together, said arms being provided with transversely elongated apertures 110

or slots —12— for receiving a loop —13— of a hame strap —14—, the latter being usually attached to the hame in any well known manner not necessary to herein illustrate or describe.

The spaces, as —15— between the periphery of the roller and inner edges of the arms —9— and —10— are of sufficient width to receive a rein or line strap —16— and to 10 permit the same to ride freely therethrough against the inner face of the roller —3—, as shown more clearly in Figures —1— and —2—.

These spaces —15— between the periphery 15 of the roller and arms —9— and —10— are open at one end only, the open end of one section being at one end of the roller, while the opening in the other section is at the opposite end of the roller, which permits the 20 rein or line —16— to be inserted in said spaces through the open ends thereof when the sections —1— and —2— are unfolded, as for example in the position shown in Figure —3—, without detaching or withdrawing 25 the line from the bits or other parts of the harness through which it is carried although it is necessary to disengage the loop —13— of the spreader strap from the slotted plates —9— and —10—.

30 When the rein is inserted in the open ended slots —15— and engaged with the inner face of the roller, the sections —1— and —2— may be folded one upon the other to bring the plates —9— and —10— into 35 close contact, after which the spreader strap —14— may be looped through the slots —12— and attached to the hame in any well known manner.

This loop —13— serves in a measure to 40 hold the sections —1— and —2— against axial displacement from the roller —3—, but in practice I prefer to provide one of the plates, as —9—, with an aperture —17— for receiving a boss or projection —18— on the 45 other plate —10— when the plates are folded one upon the other, whereby the interlocking parts —17— and —18— will serve to additionally hold the sections against relative endwise displacement from the 50 roller; the sheet metal sleeves or bushings —4— are preferably cut and formed to the desired size, before placing them upon the pintles —6—, and in assembling them upon the pintles, they are sprung open along the 55 slit, as —19— sufficiently to allow them to slip over the annular shoulders —7— and upon the main bodies of the pintles with their outer ends against the shoulders —8—, whereupon they automatically contract by 60 their own spring tension upon the periphery of said pintles.

The bore in the roller —3— is preferably made of slightly smaller diameter than the external diameter of the sleeves or bushings —4—, which, when placed upon their respective pintles, are, together with said pintles, forced under pressure into the bore —5—, thereby causing a frictional lock between the periphery of the sleeves and interior walls of the bore to cause the sleeves to rotate with the roller upon the pintles —6—, said sleeves constituting metal bearings for the pintles to better resist wear at all points throughout the length of the roller and to enable the roller to rotate with greater freedom 75 and with less lost motion than would be the case if the metal bushings were omitted, it being understood that these rollers are usually made of hard wood to reduce the weight and noise incidental to their operation. 80

What I claim is:

1. In a device of the character described, the combination of a roller having a central lengthwise opening, separate U-shaped members, each having one of its arms provided with annular shoulders in spaced relation, split bushings journaled upon the shouldered arms between the shoulders thereof, said bushings being tightly fitted in the lengthwise opening of the roller, each of the U-shaped members being rotatable about the axis of the roller within its bushing and having its other arm provided with a lengthwise slot, said slots being registered with each other when the members are folded one upon the other to receive a supporting member. 90

2. In a device of the character described, the combination of a roller having a central lengthwise opening, separate U-shaped members, each having one of its arms provided with annular shoulders in spaced relation, split bushings journaled upon the shouldered arms between the shoulders thereof, said bushings being tightly fitted in the lengthwise opening of the roller, each of the U-shaped members being rotatable about the axis of the roller within its bushing and having its other arm provided with lengthwise slots, said slots being registered with each other when the members are folded one upon the other to receive a supporting member, and means on the last named arms for holding them against relative lateral displacement when adjusted for use. 110

In witness whereof I have hereunto set my hand this twelfth day of June, 1920.

SAMUEL W. REYNOLDS.

Witnesses:

MARGUERITE HUTCHINGS,
SARAH J. SANGUINET.
